ENVELOPE

Leon Mandelbaum, New York, N. Y.

Application June 2, 1938, Serial No. 211,313

5 Claims. (Cl. 229—72)

My invention relates to improvements in envelopes, and more particularly to a dual mailing envelope.

One of the objects of my invention is to provide a novel mailing envelope which can carry two classes of mailing matter.

Another object of my invention is to provide an envelope of novel construction, having a main envelope adapted to carry printed matter, circulars or the like, and a second or supplemental envelope contained within said main envelope and adapted to carry first class mailing matter such as letters, invoices or the like.

Another object of my invention is to provide a duplex envelope having a main envelope and a second or supplemental envelope formed from an extension of the front wall of the main envelope, said second envelope being contained wholly within the main envelope and the sealing flap of the main envelope serving as the common sealing flap for both the main envelope and the second envelope.

Another object of my invention is the provision of a dual mailing envelope which can be formed from a single blank or sheet of paper or other suitable material and which is simple and economical to manufacture and sturdy in construction.

Other objects of my invention will be set forth in the following description and drawings which illustrate a preferred embodiment thereof, it being understood that the above statement of the objects of my invention is intended to generally explain the same without limiting it in any manner.

Fig. 1 is a rear plan view of the improved dual mailing envelope, part of the sealing flap being shown torn away.

Fig. 2 is a front plan view of that portion of the envelope which contains the second or supplemental envelope.

Fig. 3 is a sectional view on the line 3—3 of Fig. 1.

Fig. 4 is a perspective view of the envelope, showing the sealing flap in open position and a part of the rear wall of the envelope rolled back to show the envelope in detail.

Fig. 5 is a plan view of the cut-out blank from which the dual envelope is formed.

Referring to the drawings, my improved envelope comprises two body portions 10 and 11, body portion 10 forming the front wall of the envelope and body portion 11 forming the rear wall of the envelope. Sections 10 and 11 can be folded on each other along the scored line *a* as

shown in Fig. 5. The front wall 10 is provided with a wing or extension 12 along its upper edge and said section 12 can be folded on the front wall 10 along the scored line *b*, thus forming the inner wall of the supplemental envelope. Section 12 can have any suitable adhesive applied thereto along its upper longitudinal edge before it is folded inwardly, so that it can be securely connected to the inner face of the front wall 10. This adhesive is applied before the blank is folded. A flap 11' integral with section 12 extends laterally from said section 12 and the construction of flap 11' will be hereinafter explained. The front wall 10 is provided along its lower edge with a flap 14 and said flap 14 can be folded on the front wall 10 along the scored line *c*. The lines *a*, *b*, *c*, need not be scored, as they can be merely fold lines.

The front wall 10 is also provided with a sealing flap 15 along its longitudinal edge and said flap 15 can be folded on the front wall 10 along the line *d*. Flap 15 is provided with any suitable adhesive 16 along its free longitudinal edge, as illustrated in Figs. 4 and 5, so that it can be pasted down and secured to the rear wall 11 of the envelope, thus sealing the envelope.

The rear wall 11 is provided along its upper edge and adjacent to wing 12, with a flap 11' which can be folded on said wall 11 along the line *e*. It will be noted that wing 12 and flap 11' are integral with each other above the fold lines *e* and *b*, as shown in Fig. 5, so that both must be folded on walls 10 and 11 in one operation. In effect, fold line *e* is an extension of fold line *b*. The advantage of this construction will be hereinafter explained.

As clearly shown in Figs. 1, 2 and 5, a window 13 is provided in the front wall 10, near the upper edge thereof and adjacent wing 12.

My improved dual mailing envelope is formed as follows:

Starting with a cut-out blank of the type and form illustrated in Fig. 5, flap 11' and wing 12 are folded in unison along the lines *e* and *b* upon the inner faces of the rear wall 11 and front wall 10 respectively. The free edge of wing 12 is secured to the inner face of front wall 10 by any suitable adhesive which is applied along the inner upper longitudinal edge of said wing 12. The main portion of the body of said wing is therefore not connected to front wall 10 save at its lower longitudinal edge. Flap 14 is then folded along line *c* on the inner face of the front wall 10. Then rear wall 11 is folded inwardly along the fold line *a* so that folded flap 11' will

abut the upper portion of the outer face of wing 12, and the bottom edge of rear wall 11 will abut the outer face of flap 14. In order to join rear wall 11 to front wall 10 thus forming main envelope 18, any suitable adhesive is applied between the outer face of flap 11' and wing 12. After the rear wall 11 has been secured in position, it will be noted that the two independent envelopes have been formed, namely, supplemental envelope or pocket 17 and main envelope 18, as clearly illustrated in Fig. 4. Supplemental envelope or pocket 17 is intended to carry first class matter, such as letters, invoices, etc., and main envelope 18 is intended to carry advertising circulars, booklets, printed matter, etc.

Sealing flap 15 serves as a common sealing member for both pocket 17 and envelope 18. The edge of wing 12 which is adjacent sealing flap 15 may be recessed as shown in Fig. 4, so that ready access may be had to the letter in pocket 17. The letter is inserted within pocket 17, so that the name of the addressee is visible through the window 13 in the front wall 10.

The envelope is of sturdy construction, as shown in Fig. 3, because of the number of layers formed by flap 11' and wing 12. Additional strengthening and securing means are thus provided. Furthermore, the use of flap 11' provides the main envelope with additional mailing space. Pocket 17 is formed by the wing 12 which forms the inner wall of said pocket and by a portion of the front wall 10 of the main envelope which forms the outer wall of said pocket. Main envelope 18 is formed by the walls 10 and 11, wing 12, and the inner faces of flaps 11' and 14.

It will be noted that pocket 17 is shown as being parallel to the transverse axis of the envelope and is formed at one end of the envelope. I do not wish to be limited in this respect, as it is quite obvious that the supplemental envelope may be formed at either end of the envelope and may have its longitudinal axis parallel to the longitudinal axis of the main envelope if the sealing flap is located at either side of the envelope. The main portion of the inner end of pocket 17 is free and is not secured to the inner face of wall 10. It will be noted, however, that a portion of the inner end of pocket 17 is closed in view of wing 12 being integral with flap 11' as shown in Figs. 1 and 2. The length of pocket 17 may be varied, but I prefer the same to be substantially equal to the width of the envelope, as illustrated in the drawings.

An examination of the blank illustrated in Fig. 5 immediately reveals the simplicity of my improvement and the economy that can be effected in the manufacture of the same.

Suitable indicia may be printed on the outer face of front wall 10 if desired.

While I have shown and described a preferred embodiment of my invention, it is obvious that various modifications may be made in construction, and arrangement of parts, and in proportions, without departing from its spirit.

5

I claim:

1. An envelope of the character described, comprising a main envelope having a front wall and a rear wall and a closure flap therefor, a supplemental envelope formed within said main envelope, said supplemental envelope comprising an inner wall and an outer wall, the inner wall being formed from an extension of the front wall of the main envelope, a portion of the front wall of the main envelope serving as the outer wall of the supplemental envelope.

10

2. An envelope of the character described, comprising a first envelope having a front wall and a rear wall, a lateral extension carried by said front wall, a lateral flap carried by said rear wall, said flap and extension being integral with each other, a second envelope formed within said first envelope, said second envelope comprising an inner wall and an outer wall, the inner wall of the second envelope being formed from the lateral extension carried by the front wall, the outer wall of said second envelope being formed by a portion of the front wall of the first envelope, and a common closure member for the first and second envelopes.

30

3. An envelope as claimed in claim 2, in which an opening is provided in the front wall of the first envelope, said opening being located within the outer wall of the second pocket.

4. An envelope as claimed in claim 2, in which the lateral extension on the front wall of the first envelope is of greater width than the lateral flap on the rear wall of said first envelope.

35

5. A dual mailing envelope comprising a main enclosure having a front wall and a rear wall, a lateral wing extending from the front wall, a lateral flap extending from the rear wall, said lateral wing and lateral flap being integral with each other, a flap extending from the side of the front wall oppositely disposed to the side from which the lateral wing extends, a pocket formed within said main enclosure, said pocket comprising an inner wall and an outer wall, the inner wall of the pocket being formed from the lateral wing on the front wall of the main enclosure, the outer wall of the pocket being formed from a portion of the front wall of the main enclosure, the outer wall of the pocket having a sight opening therein, the longitudinal axis of the pocket being perpendicular to the longitudinal axis of the main enclosure, and a common closure member for the main enclosure and pocket.
